UNITED STATES PATENT OFFICE.

ANSON MARSTON, OF AMES, IOWA, ASSIGNOR TO IOWA STATE COLLEGE OF AGRICULTURE AND MECHANIC ARTS, OF AMES, IOWA, A CORPORATION OF IOWA.

CONCRETE-CONDUIT REINFORCEMENT.

Application filed September 12, 1924. Serial No. 737,372.

To all whom it may concern:

Be it known that I, ANSON MARSTON, a citizen of the United States, and a resident of Ames, in the county of Story and State of Iowa, have invented a certain new and useful Concrete-Conduit Reinforcement, of which the following is a specification.

The object of my invention is to provide a reenforcing device of simple, durable and inexpensive construction that may be readily, quickly and easily applied to concrete conduits or the like, especially those with cross sections curved circumferentially.

More specifically it is my object to provide a reenforcement comprising a metallic body portion designed to be extended circumferentially through the concrete conduit and being provided with a series of radially extended jaws rigidly secured to the body portion, and so arranged relative to the body portion and the concrete material, that when pressure is applied to the concrete tending to distort it from its original curved shape, said radially extended jaws will tend to resist and oppose distortion of the reenforcement from the original curve by adhesion and compression between them and the solid concrete material, thereby opposing radial resisting forces to the tendency to distortion of the reenforcement from the original curve, and whereby with a minimum amount of reenforcing metal the concrete conduit or the like may successfully resist such strains as would collapse and crack similar concrete structures reenforced with the ordinary reenforcing bars.

My invention consists in the construction of the reenforcing bars having radial jaws, and in the arrangement and combination thereof in a concrete structure, whereby the objects contemplated are attained, as hereinafter more fully set forth, pointed out in my claims, and illustrated in the accompanying drawings, in which:

Figure 1 shows an isometric view illustrating a reenforcing bar having integral concrete engaging jaws extended outwardly from it.

Figure 2 shows an end elevation of a part of a concrete conduit, a portion thereof being broken away and shown in section to illustrate the arrangement of my improved reenforcement in a conduit.

Figure 3 shows a side elevation of a concrete conduit with a portion thereof broken

away to show a series of my improved devices embedded therein.

Figure 4 shows a detail side view of a portion of my improved reenforcing device. The dotted lines in this figure show the relative movements of the bar body and the radial jaws when the body is bent to form a greater curve; and

Figure 5 shows a similar view including the outer bar, in which the dotted lines indicate the movement of the relative parts when pressure is applied thereto tending to form a less curve.

Referring to the accompanying drawings, I have used the reference numeral 10 to indicate the body portion of the reenforcing bar. Formed integral with this body portion at both edges and preferably staggered, is a series of jaws 11 extended substantially at right angles to the body portion, and having their tips bent outwardly from the longitudinal body 10. The width of each jaw is preferably approximately equal to the space between two jaws, and these jaws have a length depending upon the curvature extending a substantial distance into the concrete beyond the body portion 10.

The reference numeral 12 indicates a concrete conduit of ordinary construction.

In applying my improved reenforcement to a concrete conduit, I preferably extend the body portion 10 circumferentially around the mold in which the conduit is to be formed, with its inner face spaced apart a short distance from the inner surface of the mold; and then adjacent to the outer surface of the mold but spaced apart therefrom is an ordinary reenforcing bar 13, which may or may not be staggered with reference to the body portion 10. The outer reenforcing bar 13 must have sufficient inner bearing area against the concrete to provide safely against cutting into said concrete with consequent distortion from the original curve. These reenforcement devices are preferably spaced apart a short distance from each other in a direction longitudinally of the culvert, as shown in Figure 3.

In practical use, and assuming that a conduit is provided with my improved reenforcement as illustrated and described herein, and assuming further that a strain was applied to the top of the conduit, then obviously there would be a tendency to

lengthen the curvature at the top of the conduit and to shorten the curvature at the opposite sides of the conduit. In other words, such strains would tend to distort the conduit into a substantially oval shape, the greatest diameter of which is in approximately horizontal lines. When such strains are applied to my improved conduit then on the parts thereof where the strains would tend to lengthen the curvature of the body, the body portion 10 of the reenforcement would tend to move inwardly, as shown by the arrow "f" in Figure 4, which movement will be firmly resisted by the jaws 11, which grip the concrete by adhesion and compression against the bent top and between the edges, as indicated by the arrows "g" and "h". Where the strains would tend to shorten the curvature, as shown in Figure 5, the reenforcement would tend to move toward the left, as shown by the arrow "a" in Figure 5, and toward the right as shown by the arrows "b" in Figure 5. The strains tending to cause this curvature would then tend to move the central one of the jaws, shown in Figure 5, toward the left as shown by the arrow "c", and would also tend to move the free end of the upper jaw upwardly, as shown by the arrow "d" in Figure 5, and the free end of the lower jaw downwardly as shown by the arrow "e" in Figure 5. Obviously, all of these movements of the jaws would be opposed by the body of the concrete. For instance, the upper jaw shown in Figure 5 could not have its free end move upwardly without crushing the concrete material adjacent to it, and the lower jaw could not move downwardly without crushing the concrete material adjacent to its under edge.

In the parts of the conduit where the strains would tend to cause the outer bar 13 to move inwardly, as shown by the arrow "k" in Figure 5, this movement will be opposed by direct bearing of the inner face of the bar against the concrete which is of sufficient thickness under the bar 13, safely to resist such movement when the inner bearing area is adequate.

It is well known that concrete material has a very great efficiency in resisting crushing strains, but a much less efficiency in resisting tension strains tending to pull it apart. With my improvement I have taken advantage of this great efficiency of concrete material in resisting crushing strains, and have so arranged my reenforcement that concrete provided with my improved reenforcement cannot be distorted permanently out of its original shape unless such pressure and strains are applied to it as will overcome this great efficiency of the concrete in overcoming crushing strains.

Obviously, my improvement may be applied to concrete structures of any curva-

ture, and in all instances any strains tending to distort the original shape of the concrete would be resisted by the jaws exercising adhesive and crushing strains upon the body of the concrete.

I have determined by experiment that concrete conduits reenforced in the manner herein disclosed and subjected to strains sufficient to produce the first visible crack in the conduit, will withstand substantially double the amount of strains of similar conduits formed with the kind of reenforcements now in general use.

I claim as my invention:

1. An improved concrete structure comprising a concrete body, a reenforcing bar embedded therein and having a series of jaws extended substantially at right angles to the bar and rigidly secured to the bar, said parts being so shaped and arranged that when strains are applied to the concrete body tending to distort it from its original shape, the free ends of the jaws will provide, through adhesion to the adjacent concrete body and compression against the adjacent concrete body, firm resistance to distortion of the reenforcing bar from its original curvature.

2. An improved concrete structure, comprising a concrete body, a reenforcing bar embedded therein and having a series of jaws extended substantially at right angles to the bar and rigidly secured to the bar, said parts being so shaped and arranged that when strains are applied to the concrete body tending to distort it from its original shape, the free ends of the jaws will provide, through adhesion to the adjacent concrete body and compression against the adjacent concrete body, firm resistance to distortion of the reenforcing bar from its original curvature, and an outer reenforcing bar having sufficient inner bearing area against the adjacent concrete body to resist distortion inwardly from its original curved shape, said outer reenforcing bar embedded in the concrete body substantially in line radially from the first mentioned reenforcing bar and having a relatively wide inner bearing face, for the purposes stated.

3. An improved concrete structure, comprising a concrete body, a reenforcing bar embedded therein and having a series of jaws extended substantially at right angles to the bar and rigidly secured to the bar, said parts being so shaped and arranged that when strains are applied to the concrete body tending to distort it from its original shape, the free ends of the jaws will provide, through adhesion to the adjacent concrete body and compression against the adjacent concrete body, firm resistance to distortion of the reenforcing bar from its original curvature, and an outer reenforcing bar having sufficient inner bearing area against

the adjacent concrete body to resist distortion inwardly from its original curved shape.

4. An improved reenforced concrete conduit, comprising a conduit body portion formed of concrete material and having a series of circumferentially arranged bars spaced apart from its inner circumference, said bars being formed with jaws extended radially into the concrete body and rigidly connected to the reinforcing bars, said jaws having a width circumferentially of the

conduit much greater than their thickness longitudinally of the conduit, substantially as and for the purposes stated. 15

5. A reenforcement device for concrete structures comprising a body portion and a series of jaws extended approximately at right angles thereto and rigidly secured to the body portion, the outer ends of said jaws being inclined away from the body portions of the jaws, for the purposes stated. 20

ANSON MARSTON.
